SEWING MACHINE

Joseph H. Pikul, Boston, Mass., assignor to The
Reece Button Hole Machine Company, Boston,
Mass., a corporation of Maine

Application December 1, 1938, Serial No. 243,311

1 Claim. (Cl. 112—76)

This invention relates to sewing machines of the type designed to sew a suitably positioned line of stitches around an area or opening, such as a buttonhole or an eyelet, in the work, and more particularly to the work holding and clamping mechanism employed in such machines.

In buttonhole and similar machines as heretofore usually constructed, the work clamping mechanism comprises a two-part work or clamp plate the sections of which are positioned at opposite sides of the buttonhole slit or other opening in the work and cooperate respectively with a pair of spaced clamping feet between which and said plate sections the work is clamped. In such machines it is customary, after clamping the work, to spread the clamps, i. e., to move the plate sections and their respective cooperating clamping feet slightly away from one another to stretch or tension the fabric in a direction transverse to the length of the buttonhole. The use of spaced work plate sections and spaced clamping feet leaves the work unclamped at the ends of the stitching area, i. e., the region in which the stitches are positioned, with the result that there is a tendency to distort the work, the stitches, although uniformly spaced by the needle, being improperly positioned in the work when the tension is released. Moreover, tensioning of the fabric in one direction only is particularly unsuitable to the formation of circular eyelets or the like. The present invention has for an object to simplify the machine by eliminating the spreading of the work clamp and the mechanism for performing this function, and to provide an improved work clamping mechanism, comprising a unitary work plate and a cooperating unitary clamping member, whereby the fabric will be tightly and securely held at substantially all points surrounding the stitching area, and will be suitably stretched or tensioned in all directions as an incident to the clamping operation itself.

Machines of the type under consideration also include cutting mechanism, comprising a pair of cooperating cutting elements located respectively above and below the work, as well as stitching mechanism having a throat plate likewise located below the work, said cutting and stitching mechanisms, on the one hand, and the work plate or clamp, on the other, being relatively movable in directions parallel to the work plate to bring the cutting elements and the throat plate alternately into position to operate upon the work at the point where the buttonhole or the like is to be formed. Since the work is supported upon the

top surface of the work plate, its bottom surface is necessarily spaced from the bottom surface of said plate a distance corresponding to the thickness of the latter. Consequently, the work plate must have elongated openings therethrough in which the throat plate and lower cutting element can move into and out of operative position, or said throat plate and cutting element must be given movements transverse to the work plate in addition to their relative movements parallel thereto: otherwise they, when in operative position, will be spaced too far from the work for accurate and satisfactory operation unless the work plate is made unduly thin. The present invention has for another object the provision of a construction employing a work plate of adequate thickness and, except in the region of the stitching area, of substantially unbroken continuity as to its work supporting surface, wherein the throat plate and lower cutting element are at all times beneath the work plate and move relatively to the latter only in planes parallel thereto, but wherein the bottom surface of the work is positioned substantially flush with said cutting element and throat plate when said parts are in operative position with respect thereto.

The foregoing and other objects of the invention, together with means whereby the latter may be carried into effect, will best be understood from the following description of an illustrative embodiment thereof shown in the accompanying drawings, this, however, having been chosen for purposes of exemplification merely, as it will be obvious to those skilled in the art that the invention, as defined by the claim hereunto appended, may be otherwise embodied without departing from its spirit and scope.

In said drawings:

Fig. 1 is a side elevation, partly in section, of a machine including work clamping mechanism embodying the invention.

Fig. 2 is a plan view, partly broken away, of the work clamping mechanism per se and associated parts.

Fig. 3 is a section taken substantially on the line 3—3, Fig. 2, showing the parts in a different position.

Figs. 4 and 5 are views similar to Fig. 3 showing the parts in different positions.

Fig. 6 is a section taken substantially on the line 6—6, Fig. 5.

Referring to Fig. 1, the invention is shown as applied to a buttonhole or similar machine of a well known type comprising a stationary bed frame 15 carrying the work clamping mecha-

nism, hereinafter described, and a movable stitch frame or head 16 carrying the stitching mechanism as well as cutting mechanism for cutting the buttonhole or the like. The stitch frame 16 is movable longitudinally over the bed frame 15 to bring the stitching and cutting mechanisms alternatively into operative relationship with the work, and also both longitudinally and laterally to position the stitches in accordance with the work to be performed, by means of mechanism operated by a main cam 17 carried by the stitch frame 16 and rotated by a feed shaft 18 likewise carried by said frame. This mechanism is well known in the art, being shown, for example, by the patents to Reece, No. 240,546, April 26, 1881, and No. 655,637, August 7, 1900, and many others, and requires no detailed description herein.

The stitching mechanism comprises a needle 19 carried by a needle bar 20, and looper mechanism 14 which may be substantially as shown in the patent to Grip, No. 1,905,854, April 25, 1933, said needle bar and looper mechanism being carried respectively by upper and lower turrets 21 and 22 rotated in unison at the proper time by gear segments 23 and 24 carried by a rock shaft 25 operated by the main cam 17 as further described in the Reece patents above referred to. The lower turret 22 also carries a throat plate 26 through which the needle 19 passes to cooperate with the looper mechanism. The needle bar 20 is reciprocated vertically and vibrated laterally in its turret 21 by means of suitable cams on a stitching shaft 27 through mechanisms generally indicated at 28 and 28a, respectively, and which may be substantially as shown and described in the patent to Reece No. 1,991,627, February 19, 1935. The looper mechanism carried by the turret 22 is likewise operated from the stitching shaft 27 by mechanism generally indicated at 29 and which may be substantially as shown and described in the patent to Grip above referred to and in the patent to Dunnell No. 1,935,083, November 14, 1933.

The cutting mechanism comprises upper and lower cooperating cutting elements 30 and 31, the former of which is carried by a lever or arm 32 operated at the proper time from the main cam 17, as described more fully in the patent to Kiewicz, No. 1,841,133, January 12, 1932.

The work clamping mechanism, hereinafter more fully described, and which, as above stated, is carried by the bed frame 15, includes a work or clamp plate 33 and cooperating clamping means carried by a pair of arms 34 pivoted at 35 to said work plate and operated by mechanism including a swinging frame or rocker 36, toggle 37 and lever 38 which in turn is operated by the cam 17, the latter mechanism, as herein shown, being substantially as more fully described in the Kiewicz patent above referred to and in the patent to Hill, No. 713,764, November 18, 1902.

It will be understood that, in machines of this character, suitable mechanism is provided whereby the machine, when started, will perform its operative cycle and then automatically stop, said cycle including, first, a closing of the work clamp to clamp the work, then a movement of the stitch frame from the cutting position shown in Figs. 1, 3 and 5, in which the cutting elements are adjacent the stitching area, into a stitching position in which the stitching instrumentalities are adjacent said area, a stitching operation of a character determined by the design of the feed mechanism, a return of the parts into cutting position, and, finally, the opening of the work clamp

to release the work, said cycle also including a cutting operation which may be performed either before or after the stitching operation according to the design or adjustment of the machine.

Except as hereinafter pointed out, or as they enter into combination with parts hereinafter described, the mechanisms above referred to specifically form no part of the present invention and may be as shown and described in the patents referred to, or otherwise, as will be well understood by those skilled in the art.

In accordance with the present invention, the work plate 33 comprises a single unitary member (i. e., it is not divided into relatively movable sections) removably positioned on the bed frame 15 by lugs or dowels 39 projecting upwardly from the latter and received in openings 40 in said work plate. Adjustably secured, as by screws 41, to the rear or inner end of the work plate are lugs 42 to which the arms 34 are pivoted, said plate having slots 43 through which the lower ends of said arms project for detachable engagement with the rocker 36, permitting removal of said arms with the work plate. At its underside, the work plate 33 is grooved, as shown at 44, to receive the throat plate 26 and lower cutting element 31 and permit movement of said plate and element alternatively into operative position, the portion of said plate above said groove being, however, of substantial thickness, and its bottom surface being substantially flush with the tops of said plate and element, except for the necessary clearance which is somewhat exaggerated in Figs. 3 and 5.

The portion of the work plate 33 last referred to is provided with an opening 45 therethrough, said opening being preferably, and for convenience, formed in a removable portion or slide 46 which, however, is normally stationary with respect to the plate so as to constitute a unitary part thereof, being secured in this position by a spring 40 pressed latch 46a as shown in Fig. 2. The opening 45 is formed with downwardly converging, preferably serrated edges, and cooperating therewith is a unitary clamping member 47 of substantially complementary form, pivoted at 48 to the arms 34 and extending between them, said member having therethrough an opening 49 which, when said member is in clamping position, is aligned with the opening 45 and with the cutting element 31 when the latter is in operative position as shown in Figs. 3 and 5.

The opening 49 is of a suitable size and shape to enclose the stitching area and, therefore, to receive all of the stitches positioned by the feeding movements of the stitch head and the rotation of the turrets in accordance with the character of the work to be performed. The particular machine herein shown is arranged to sew circular eyelets, and the opening 49 is accordingly of circular shape. To the same end, the lower cutting element 31 comprises a round punch to cooperate with a cutting block or anvil 30 carried by the lever 32, said punch having a shank received in a socket 50 carried by the stitch frame 16 and secured therein by a set screw 51, a series 65 of interchangeable punches of different sizes being preferably provided, said punches, however, all having shanks of a size to fit the socket 50, so as to be automatically centered merely by insertion into said socket. It will, of course, be understood that for sewing buttonholes or the like of shapes other than circular, work plates and clamping members having openings 45 and 49 of appropriate shapes can be substituted for those shown and that the punch 31 can be re-

placed by cutters likewise of suitable form in accordance with the usual practice.

The opposed coacting edges of the opening 45 and clamping member 47 are continuous except 5 for narrow registering thread channels 52 and 53 to accommodate the needle thread when the parts are moved from stitching to cutting position. Consequently, it will be seen that said edges are adapted to engage and clamp the work 10 W substantially continuously throughout a region completely surrounding the stitching area.

The work W having been positioned on the work plate 33 with the clamping member 47 elevated, as shown in Fig. 3, the clamp operating 15 mechanism is operated to press said member into engagement with the work, as shown in Fig. 4, the pivotal mounting 48 of said member permitting the latter to engage the work evenly, said member being thereafter further depressed into 20 the position shown in Fig. 5 to clamp the work at the edge of the opening 45 between its peripheral surface and said edge, ultimately displacing or depressing said work into said opening into a position with its bottom surface sub- 25 stantially flush with the bottom surface of the

work plate and, therefore, with the tops of the throat plate 26 and cutting element 31. Consequently, the movements of the throat plate and cutting element into and out of operative position, i. e., into and out of register with the opening 45, need be only in a plane parallel with the work plate, said members, however, being in close proximity to the work when brought into operative position. The final downward movement of the clamping member after the work W has been gripped between it and the edge of the opening in the work plate acts to stretch said work across the opening 49 like a drum head, thereby tensioning the same substantially equally in all directions, this action being incidental to the clamping 10 operation itself and without any spreading of the clamp.

I claim:

In a sewing machine, the combination with a work plate having therethrough an opening with 20 downwardly converging serrated edges, of a work clamping member having an exterior form substantially complementary to said opening.

JOSEPH H. PIKUL. 25
